FLUID COOKING PROCESS WITH QUENCHING OF HYDROCARBON VAPORS

Charles E. Jahnig, Red Bank, N. J., assignor to Esso Research and Engineering Company, a corporation of Delaware

Application December 30, 1953, Serial No. 401,305

2 Claims. (Cl. 196—55)

This invention relates generally to the transporting and cooling of hot hydrocarbon gases having a tendency to form coke deposits on the conduits and equipment containing them. More particularly it relates to methods and means for transporting and cooling of the hot product gases from fluid coking operations.

The fluid coking process for heavy hydrocarbons has recently been proposed. Briefly stated, hydrocarbon oils are upgraded by this coking process, utilizing the fluidization technique, to lighter, more valuable products by injecting the oils into a reactor vessel containing a bed of hot finely divided fluidized solids. Pyrolysis of the oil occurs in the vessel and carbonaceous residue is deposited on the fluidized solids and lighter gasiform hydrocarbons are evolved and withdrawn as product. The reaction temperature of the bed is maintained by continuously withdrawing a portion of the carbon-containing solids and circulating them to an external heater and back.

One of the problems in fluid coking is the building up of coke deposits in the system that handles the product hydrocarbon gases before they are cooled below a critical coking temperature, i. e., below 700° F. Some of the hydrocarbons in the coker overhead vapors are high boiling and will readily condense. If condensation occurs in a critical coking range of about 700°—1000° F., the condensate cokes, causing fouling and plugging of the equipment. So long as the gases remain above the critical temperature range, coking will not occur. But in cooling the gases, coking will occur while the gases pass through this range if there are attendant surfaces for the coke to form on.

This problem is aggravated somewhat by the fact that the hydrocarbons in this overhead product are reactive and may tend to polymerize. In this way, molecular weight is raised and gases, which at first were at or above their dew point, are converted to a mixture of part liquid and vapor which can condense and cause coke formations.

Particularly troublesome places where this coking occurs is in the product transfer lines from the fluid coking reaction vessel to the quenching (or fractionating) zone and at the nozzle introducing the vapors into the quench zone.

One method of caring for this difficulty is to add a volume of superheated steam or other light inert gas to the reactor outlet products to dilute them. This operates to lower the dew point of the gaseous mixture thereby inhibiting condensation. This, however, is costly and leads to greater expense in the recovery of products.

This invention is based upon the discovery that coke deposits by the gases can be attributed to surface temperatures in a critical range. If a surface is above the dew point temperature of the gases, condensation and, consequently, coking does not occur. If the temperature is about 600° F., or less, the reaction rate is slow enough so that serious coke deposits do not form. Within a

2

critical surface temperature range of about 700—1000° F., there is condensation and sufficient coking to build up a deposit.

Accordingly, an object of this invention is to prevent coking and fouling of equipment containing high temperature hydrocarbon vapors. A more specific object is to prevent carbon deposition by hot hydrocarbon gases on the surfaces of confining vessels and conduits by judicious control of surface temperatures. Another object is to provide a method for cooling hot hydrocarbon vapors to a temperature below a critical coking temperature without the accompanying formation of coke deposits. Other objects and advantages will appear more clearly as the attached drawings, forming a part of this specification, are discussed in detail.

Generally stated, the objects of this invention are attained in a system handling high temperature hydrocarbon vapors from a reactor by maintaining the temperature of confining surfaces above the dew point of the vapors prior to quenching the vapors, so that condensation and coking in the liquid phase is avoided, quenching the vapors from the reaction temperature to about 700°—750° F., in such a manner that the transition through the critical coke deposition range is in the vapor phase, and thereafter maintaining the temperature of confining surfaces below about 700° F. Preferably, the surfaces of equipment immediately following the quenching zone are washed with liquid.

This invention is concerned with a novel quench nozzle depicted in the attached drawings, and its use in such a manner that problems of coke deposition by high temperature hydrocarbon vapors are avoided.

In the drawings,

Figure 1 depicts in cross-section a nozzle arrangement constructed according to the principle of this invention. The nozzle is used to horizontally introduce high-temperature vapors into a scrubbing or fractionating zone.

Figure 2 illustrates another arrangement for introducing hot gases into a quench zone.

Figure 3 portrays a conventional quenching arrangement and will be used to emphasize the advantages of the arrangement of Figure 2.

Figure 4 illustrates the use of this invention in a hydrocarbon oil fluid coking process.

In Figure 1, the hot hydrocarbon gases are being transported by pipe 2. All surfaces of the equipment in contact with the gases prior to this point are to be understood to have been maintained at a temperature above about 900° to 1000° F.

It is to be understood that the critical temperature will vary with specific processes. For example, the dew point or condensation point of gases from a fluid coker operating at a temperature of about 950° F., will be about 950° F. For a coker operating at a temperature of 900° F. the dew point will be about 900° F. It is sufficient to keep surface temperatures above this dew point. Heating means 6 is depicted for keeping the surface of pipe 2 above the dew point of the gases. A steam coil wrapped around the pipe is the preferred mode of heating, although other means can be used such as an electric heating element. Insulation can be used to help maintain the desired temperature. For example, the outside of the heating coil 6 or the inside of pipe 7 can be insulated.

Pipe 2 enters a cooling zone, which can be a fractionating tower, quench tank, scrubbing tower or the like. The gases issue from the pipe and are immediately mixed with a downcomer coolant and cooled in the vapor phase. This coolant normally will be a liquid such as water or reflux in a fractionating column in the form of a spray, stream or droplets. However, the cooling can be accomplished by finely divided solid material or by a stream of cool gas such as steam. Suitable solid coolants are shot

70

having about $\frac{1}{16}$ inch diameter or coke from a fluid coking operation.

For purposes of illustration, the cooling zone is shown as being contained in a vessel 1 with an entrance port constructed of a pipe 5 and flange 4. A flange 3 is affixed to pipe 2 and matches flange 4. The flanges are held together, with suitable gasketing between them, by bolts (not shown) in holes 9. In this manner, the pipe can be mounted on the vessel 1.

An interior concentric baffle 7 is arranged over the protruding pipe to protect it and the heating means from the coolant. Bleed gas, such as steam, is admitted by line 8 to the annulus formed by the baffle to prevent gases from entering the annulus, due to any surges in the system, and coking.

While the pipe 2 is kept hot, the baffle and the walls of the vessel are kept at a temperature below 700° F. by the coolant so that coke will not form on them. Thus, it can be seen that by this invention, when product hydrocarbon vapors are in a critical coking temperature range, which for a fluid coking vessel is about 780°-900° F., there are no equipment surfaces present at this temperature upon which carbon deposition can form. In cases where it is necessary to have a surface temperature in this temperature range, the surface can be blanketed with a purge gas, e. g., steam, as was done to protect zone A of Figure 1.

In Figure 2, a line quench arrangement for the gases is shown. Hot vapors are introduced downwardly into the quench chamber 13 by pipe 11 which protrudes inwardly into the chamber. The pipe 11 is kept at a high temperature by a steam heating coil 12. A spray ring 14, supplied with a liquid coolant by line 15, is mounted just below the end of pipe 11. The gases upon emerging from the pipe are immediately cooled below their coking forming temperature by the liquid quench. Again, although it is not mandatory, bleed gas is admitted by line 16 to the space around the pipe to prevent hot gases and coolant from surging upwardly and contacting the heating means. Line 17 removes the cooled gases from the quench tank and they are then carried to further processing such as a separation step.

Figure 3 illustrates a conventional method of quenching high temperature product gases from a coker. In the drawing the vapors are being conveyed by line 22 which is heated by element 23 and are cooled by a liquid supplied by line 24. It has been found that an area, B, adjacent to the coolant inlet port has a temperature within the dewpoint of the vapors, even though the pipe is heated up to this point. Consequently coke deposits build up at this point. Also, on the side of the pipe, C, opposite from the quench port, deposits build up because the swirling and erratic motion of the liquid and vapors leaves an area having a critical temperature. In the nozzle arrangement of Figure 2, the cooling of the vapors occurs in the vapor phase. The interior walls 18 of the quench chamber 13 are further protected by a liquid film. If the swirling vapors do contact the wall, carbon deposition is prevented by the liquid film.

Thus it can be seen that by the method of this invention, high temperature gases can be effectively cooled without the accompanying formation of coke deposits.

Figure 4 shows the quenching arrangement of this invention as used to handle vapors produced by a hydrocarbon oil fluid coking process. As shown, fluid coking vessel 30 contains a fluid coking bed 32 fluidized by steam supplied by line 29. The coking bed 32 is maintained at a coking temperature. A hydrocarbon oil is injected into the coking bed by line 31. Upon contact with the heated finely divided solids, the oil undergoes vaporization and pyrolysis, depositing coke residue on the solids. Vapors

are removed overhead from the coking zone through cyclone 35, and then passed by line 36 to a vapor cooling vessel 40.

According to this invention, line 36 is heated by heating elements 37. The terminal portion of line 36 projecting into vessel 40 is protected by a cylindrical concentric baffle 38. Bleed gas is admitted by line 39 into the annular passageway formed by this cylindrical baffle. Liquid coolant supplied by line 41 is sprayed into the vapors issuing from line 36. Cooled vapors are removed from the upper portion of vessel 40 by line 42 and the liquid coolant, along with any condensed material, is removed by line 43 from the bottom portion of vessel 40.

What is claimed is:

1. In a hydrocarbon oil fluid coking process wherein high temperature hydrocarbon vapors are produced in a coking zone and said hydrocarbon vapors have a propensity to form coke deposits on attendant surfaces, a method of preventing said coke deposits while cooling said hydrocarbon vapors through a critical coke deposition temperature range which comprises withdrawing said hydrocarbon vapors from said coking zone through a gas impervious passageway, maintaining the interior surface temperature of said passageway above the dew point of said hydrocarbon vapors by means of heating elements, injecting said hydrocarbon vapors from said passageway into a gas cooling zone at an interior point removed from the confines of said gas cooling zone, forming a second passageway in said cooling zone about said gas impervious passageway and heating elements extending into said cooling zone, said second passageway terminating and opening into said gas cooling zone at the point of termination of said gas impervious passageway, maintaining the outer confines of said passageway below 780° F., injecting a bleed gas into said second passageway to prevent entrance of hydrocarbon vapors thereto, cooling said vapors below 780° F. in the vapor phase through contact with a finely divided liquid coolant, and withdrawing cooled vapors from said cooling zone.
2. In hydrocarbon oil fluid coking system comprising a reactor vessel, a coking bed of finely divided fluidized solids therein, and a vapor cooling vessel, the improvement comprising a gas impervious cylindrical conduit extending from the upper portion of said reactor vessel and terminating within said vapor cooling vessel adapted for the passage of high temperature hydrocarbon vapors therebetween, concentric heating elements disposed about said gas impervious conduit to maintain the interior surface temperature thereof above the dew point of said high temperature hydrocarbon vapors, a cylindrical concentric baffle in said vapor cooling vessel about said gas impervious cylindrical conduit and said concentric heating elements radially spaced therefrom to form an annular passageway, said passageway opening into said vapor cooling vessel at the terminus of said gas impervious cylindrical conduit, conduit means for injecting a bleed gas into said annular passageway, means in said vapor cooling vessel for dispersing a liquid coolant in the hydrocarbon vapors issuing from said gas impervious cylindrical conduit, and conduit means for withdrawing cooled vapors and liquid from said vapor cooling vessel.
